S. G. VAN DERBECK & H. B. MURDOCK,
ELECTRICAL LOCKING DEVICE,
APPLICATION FILED JUNE 24, 1916.

1,230,449.

Patented June 19, 1917.

UNITED STATES PATENT OFFICE.

STEPHEN G. VAN DERBECK, OF HACKENSACK, NEW JERSEY, AND HARRY B. MURDOCK,
OF NEW YORK, N. Y., ASSIGNORS TO DUPLEX LOCK CO., INC., OF NEW YORK, N. Y.,
A CORPORATION OF NEW YORK.

ELECTRICAL LOCKING DEVICE.

1,230,449.

Specification of Letters Patent. Patented June 19, 1917.

Application filed June 24, 1916. Serial No. 105,616.

To all whom it may concern:

Be it known that we, STEPHEN G. VAN DERBECK and HARRY B. MURDOCK, citizens of the United States, and residents, respectively, of Hackensack, in the county of Bergen and State of New Jersey, and the borough of Manhattan, county of New York, and State of New York, have jointly invented certain new and useful Improvements in 10 an Electrical Locking Device, of which the following is a specification.

This invention relates to an electrical locking device, and provides locking means which is adapted to engage a movable bar, 15 and the latter in turn is connected to means which prevent the propulsion of a car or the like.

In the accompanying drawings Figure 1 shows a top plan view of a device with the 20 cover thereof removed, exemplifying the invention; Fig. 2 represents a section of Fig. 1 on the line 2, 2; Fig. 3 is a partial front view of Fig. 1; Fig. 4 shows a partial section of Fig. 1 as on the broken line 4, 4; 25 Fig. 5 shows some details partially in section as on the line 5, 5 of Fig. 2 and Fig. 6 represents a fragmentary portion of Fig. 1 with some of the elements omitted.

A casing is indicated in its entirety by the 30 numeral 20 and comprises the bottom 21, rear wall 22, front wall 23, end walls 24, 25 and removable top plate 26.

With the bottom are formed the lugs 27 having the openings 28, for screws or bolts 35 to attach the device to any convenient portion of the vehicle with which it is to be used. A sleeve 30 and an elongated cavity 31 with the shelves 32 are formed with the casing. The inner portion of the sleeve 30 connects with the lower portion of the cavity 31 and a guide opening 33 connects the lower portion of the cavity 31 with the interior of the casing 20.

In the casing 20 is located a solenoid 35 which has the insulated end disks 36 and 37. The disk 37 has formed therewith the foot plate 38, and is attached to the bottom 21, by means of the screws 39. The disk 36 is attached to the end wall 24 by means of the 50 screws 40.

In the wall 24 is an opening 41 coaxial with the longitudinal axis of the solenoid 35. In the said opening 41 is fastened a stop plug 42 of permeable material, by means of

a pin 44. A cone shaped depression 44^a is 55 formed in one end of the plug 42. A sleeve 45 of any non magnetic material is located in the solenoid and surrounds the said stop plug 42. An opening containing an insulating sleeve 48 is formed in the rear wall 22. 60 A latch plunger 50 is slidably located in the sleeve 45 and at one end has formed therewith the tapered end 51. The latter is formed with a sharper angle at its peak than the angle of the depression 44 of the stop 65 plug 42.

In the lower portion of the cavity 31 a latch arm 55 having the heel 56 is hinged on a pivot screw 57 extending from the bottom 21 of the casing 20.

A link 62 of non-magnetic material has one end pinned to the latch arm 55, by means of the pin 63, and its other end is pinned to the latch plunger 50 by means of the pin 64. A flange collar 65 extends from the link 62, 75 and a spring 66 encircles the plunger 50 and link 62. The ends of spring 66 bear between the disk 37 and the inner face of the boss 68 of the wall 25.

In the sleeve 30 is located a cylindrical 80 sliding bar 70 with cylindrical keeper notches 71, and which has formed at its ends the grooves 72.

Plates 75, 76 with the forked ends 77 are supported upon the ends of the bar 70. Pins 85 78 extend through the plates 75, 76 and engage the grooves 72, and thereby the said plates can be turned to different angular positions on the bar 70.

The forked ends 77 engage the rod 80, and 90 the latter is connected to the braking mechanism of a vehicle or any other member thereof of which is to be controlled.

Stop clamps each comprising the members 85 and 86 are clamped to the rod 78, by 95 means of the bolts 87.

Upon the shelves 32 of the cavity 31 is placed a plate 90, and upon the latter is placed a plate of insulating material 91. The latter insulates the sleeves 94 to be described and its appurtenances from the casing 20.

A sleeve 94 with the longitudinal opening 95 has connected to one end thereof the block of insulating material 96, and at the other end is formed a head 97. A second sleeve 98 in the sleeve 94 has extending therefrom the rod 99 with the cap 100 con-

nected thereto. The rod 99 extends through an opening in the head 97. A spring 102 in the sleeve 94 bears with one end against the sleeve 98 and the other end bears against the block 96. A block of insulating material 104 with the cover 105 of electric conducting material extends from the pin 105^a which in turn extends from the piston 98. A pair of flexible electric conductor bars 106, 107 have each one end fastened to the block 96.

5 An electric wire 110 passes through the sleeve 48 and has one end fastened to one end of the coil of the solenoid 35. An electric battery 111 is in series with the wire 110 and the said wire leads to the electric switch 112. An electric wire 115 leads from the switch 112, passes through the sleeve 48 and is fastened to the binding post 116 of the bar 106. A wire 118 extends from the binding 10 post 120 of the bar 107 and leads to the other end of the coil of said solenoid.

15 To operate the device the rod 80, which in this instance may be considered the brake rod of an automobile is moved by the operator in the usual way and to lock the brake it controls, it is moved in the direction of the arrow A. In the position of the parts shown in Fig. 1 the heel 56 of the arm 55 is riding on the smooth cylindrical surface of the bar 70. Just after the plate 75 bears 20 against the cap 100, the cover 105 makes contact with the conductor bars 106, 107, and the electric circuit of the solenoid is closed. Thereby the plunger 50 is drawn in to the 25 solenoid until it meets the stop plug 42. At the same time the heel 56 is moved out of the notches 71 and the rod 80 can be moved to lock the brake of the vehicle, the switch 112 at the same time being closed. When 30 the brake is to be maintained in its locked position the switch 112 is opened and the tension of the spring 66 forces the heel 56 into one of the notches 71. It will be noted that the electric circuit is only closed when 35 the cover 105 makes contact with the conductor bars 106 and 107 and therefore current is only being used when the bar 70 is moved to lock the brake of the vehicle. When it is desired to unlock the brake, the 40 switch 112 is again closed, which energizes the solenoid 35 and the heel 56 is pulled out of its engaging groove 71. The bar 70 is then moved in a direction opposite to that of the arrow A and the brake of the vehicle is 45 released. The function of the rotatable plates 75 and 76 is to efficiently engage the rod 80, when the latter is parallel to the bar 70 or inclined thereto. The axis of the rod 80 can make an angle with the axis of the 50 bar, by slightly separating the pair of stop clamps having the members 85 and 86, when the rod 80 can be located in the forked ends while inclined to the direction of the bar 70. The angularity is presumed to be in the 55 plane in which the bar and rod are indicated

in Fig. 1. Also the rod 80 can make an angle with said plane by reason of the plates 75 and 76 being capable of swinging on the ends of the bar 70.

Having thus described our invention what we desire to secure by Letters Patent and claim is:

1. In a locking device of the character described the combination of a casing, a solenoid in said casing, a plunger in said solenoid and operated thereby, a latch arm connected to the plunger, a sleeve formed with the said casing, a sliding bar in said sleeve having notches, one of said notches engaged by the latch arm, forked plates on the ends 75 of said bar, the brake rod of a vehicle engaged by said plates and stop blocks on the said brake rod coacting with said plates.

2. In a locking device of the character described the combination of a sliding bar 85 having keeper notches formed therein, a latch arm pivoted adjacent to said bar, a spring to lock the latch bar with said notches, a solenoid when energized unlocking the latch arm from said notches, a sleeve 90 with a rod slidably guided adjacent to said bar, an electric conductor carried by said sleeve, a plate carried on the bar in the path of said rod moving the latter at predetermined positions of said bar, an electric circuit 95 for the solenoid, and electric conductor bars in circuit with said electric circuit and in the path of the conductor carried by the said sleeve.

3. In a locking device of the character 100 described the combination of a sliding bar having notches, a latch arm pivoted adjacent to said bar with the swinging end thereof contacting with said bar, a solenoid in the device, a plunger slidably located in said 105 solenoid, a non-magnetic link with one end pinned to said plunger and its other end pinned to the latch arm, a spring to force the latch plunger out of the solenoid when the latter is not energized and thereby lock 110 the latch arm with said sliding bar, an electric circuit for the solenoid, means to move the sliding bar, and means to close said electric circuit with the movement of said bar.

4. In a locking device of the character 115 described the combination of a sliding bar having notches, a latch arm pivoted adjacent to said bar with the swinging end thereof contacting with said bar, a solenoid in the device, a plunger slidably located in said 120 solenoid, a non-magnetic member connecting the said latch arm and plunger, a spring to normally force the latch plunger out of the solenoid when the latter is not energized, a spring actuated sleeve adjacent to the said 125 latch arm, a rod extending from said sleeve, an element on the sliding bar in the path of said rod, the latter being moved with the movement in one direction of said bar, an electric conductor carried by said sleeve, a 130

pair of electric conductor bars insulated from each other in the path of said electric conductor, and an electric circuit for the solenoid, the said bars in series with the circuit, the said circuit closed with the contacting of said electric conductor and conductor bars.

5. In a locking device of the character described the combination of a sliding bar having notches, a latch arm pivoted adjacent to said bar and adapted to lock said arm in position, a solenoid coacting with said latch arm, a spring to normally lock said latch arm with said bar, an electric circuit for the solenoid, and an electric conductor moved with the movements of said sliding bar to close said electric circuit and thereby maintain said latch arm unlocked from said sliding bar.

10. In a locking device of the character described the combination of a sliding bar, means to lock said sliding bar in different positions, a plate rotatably connected to each end of said bar and means to connect

15. a movable element to said plates.

20. In a locking device of the character described the combination of a sliding bar, means to lock said sliding bar in different positions, a plate rotatably connected to each end of said bar and means to connect

25. a movable element to said plates.

7. In a locking device of the character described the combination of a sliding bar, means to lock said bar in different positions, a plate with forked ends rotatably connected to each end of said bar to engage a mov-

able rod, and stop clamps for the rod to hold it in proper position in said forked ends.

8. In a locking device of the character described the combination of a sliding bar having grooves formed at the opposite ends thereof, means to lock said bar in different positions, a plate with a forked end rotatably supported on each end of said bar, a pin extending through each plate engaging the groove of its accompanying end of the sliding bar and means to engage a rod with said forked ends.

9. In a locking device of the character described the combination of a sliding bar having grooves at its opposite ends, mechanical means to lock said bar in different positions, a plate with a forked end rotatably supported on each end of said bar, means to rotatably engage each plate with said bar, and means to engage a rod with said forked ends.

Signed at the borough of Manhattan, in the county of New York and State of New York, this 19th day of June, A. D. 1916.
